UNITED STATES PATENT OFFICE

115,125

DESIGN FOR A COIN AND SLUG DETECTOR

William Patzer and Walter A. Tratsch,
Chicago, Ill.

Application April 7, 1939, Serial No. 84,108

Term of patent 14 years

To all whom it may concern:

Be it known that we, William Patzer and Walter A. Tratsch, citizens of the Republic of Germany and the United States, respectively, and both residents of Chicago, in the county of Cook and State of Illinois, have invented a new, original, and ornamental Design for a Coin and Slug Detector, of which the following is a specification, reference being had to the accompanying drawing, forming a part thereof, and in which:

Fig. 1 is a front perspective view of a coin and slug detector, showing our new design; and

Fig. 2 is a rear perspective view thereof.

We claim:

The ornamental design for a coin and slug detector, as shown.

WILLIAM PATZER.
WALTER A. TRATSCH.
